UNITED STATES PATENT OFFICE.

SILAS C. PURDY, OF ATKINSON, NEBRASKA.

STRAW-BURNING ATTACHMENT FOR STOVES.

SPECIFICATION forming part of Letters Patent No. 344,327, dated June 22, 1886.

Application filed December 11, 1885. Serial No. 185,389. (No model.)

To all whom it may concern:

Be it known that I, SILAS C. PURDY, of 5
Atkinson, in the county of Holt and State of
Nebraska, have invented a new and Improved
Straw-Burning Attachment for Stoves, of
which the following is a full, clear, and exact
description.

My invention relates to an attachment to
stoves whereby straw, hay, or other fibrous
10 fuel may be economically burned by utilizing
the draft-passages of the stove and without
decreasing the heating or cooking capacity of
the stove.

The invention consists in certain novel fea- 15
tures of construction of the straw-burning at-
tachment and in its combination with the stove,
all as hereinafter fully set forth.

Reference is to be had to the accompanying 20
drawings, forming a part of this specification, in
which similar letters of reference indicate cor-
responding parts in all the figures.

Figure 1 is a transverse vertical sectional 25
elevation of my improved straw-burner as
applied to a stove, the latter being partly
broken away and in section. Fig. 2 is a rear
elevation of the base or fire pot of the attach-
ment; and Fig. 3 is a plan view of the stove 30
and base of the straw-burner, partly broken
away and in section.

30 The straw-burning attachment consists of a
base or fire box A, adapted to the front of an
ordinary cook-stove, and a straw or fuel res-
ervoir, B', adapted to be set, when filled and
turned bottom upward, onto the top of the 35
base A, as clearly shown in Fig. 1. The base
A is made preferably of sheet metal with a
closed bottom, a, and sides and ends formed
of a bent plate, a', which is cut away at the
40 rear side to form an opening, a², at each side
of which there is an out-turned vertical flange,
a³, at the extremity of which a hollow bead
or eye, a⁴, is formed. The opening a² corre-
sponds in size with the opening at the front 45
of the stove C when the entire front of the
stove is removed, and whereby the side flanges,
a³ a³, of the base fit against the opposite side
plates of the stove, and so that the same stove
bolts or pins D which had served to hold 50
the ordinary stove-front in place may be passed
down through the beads or eyes a⁴ a⁴ to hold

the base A to the body of the stove, while its
bottom rests on the front plate, c, of the stove.

At or near the top of the base A is fast- 55
ened by screws or bolts e the cast-iron angu-
lar flange E, which forms the seat or support
on which the open end of the fuel-reservoir B
rests, and in the front of the base A, just be-
neath this flange E, is formed an opening, as
at F, to give draft for proper combustion of
the hay or straw. When the stove-front and
the ordinary wood or coal burning grate of
the stove are removed, the draft-passage c' of
the stove over its oven c² will be unobstructed
from the base A to the exit c³, to which the
stove pipe or flue is fitted.

65 It is evident that when the fuel-reservoir B
is filled with hay or straw or like fibrous fuel
and is set inserted on the base A, as in Fig. 1,
and when the fuel ignites, the draft through
the opening F in the base will allow free com-
bustion of the fuel, and the products of com-
bustion will pass through the base A and into
and along the stove draft-passage c' and at the
front and over the top of the stove-oven c²,
and beneath all the holes c⁴ of the stove-top; 70
hence the entire heating or cooking capacity
of the stove may be made available when the
straw-burner is attached to the stove, and
which is not possible when a fuel-reservoir is
placed over the front holes of the stove-top,
75 as these holes then cannot be used for cook-
ing purposes. Furthermore, with the fuel-
reservoir-supporting base A attached to the
front of the stove there is much less liability
of choking up the draft-passages of the stove
80 than there is when the fuel-reservoir is sup-
ported directly on the stove-top, as it only is
necessary, after three or four reservoirs full of
fuel have been burned, to stir up the ashes in
the base A, and they will fly backward and
85 out of the stove-pipe fixed at the exit c³.

90 The attachment or base A may readily be
applied to or removed from the stove and may
be made very cheaply, and is durable in use.

Having thus fully described my invention, I 95
claim as new and desire to secure by Letters
Patent—

1. In straw-burning attachments to stoves,
the base or fire box A, made with an open
top, an upper support for the fuel-reservoir, 100

a draft-aperture, as at F, a rear side opening, a^2 , and flanges a^3 , provided with hollow beads or eyes a^4 , substantially as described, for the purposes set forth.

5 2. The combination, with a stove, of a base or support, A, having an open top, an upper flange, as at E, a draft-aperture, F, and a rear side opening, a^2 , flanges a^3 , provided with eyes

a^4 , the stove-bolts D, passing through said eyes, and a fuel-reservoir, B, adapted to rest on the flange E of the base A, substantially as and for the purposes herein set forth.

SILAS C. PURDY.
